BODYWORK

Marius Joseph Daste, Courbevoie, France

Application September 22, 1931, Serial No. 564,419
In France June 12, 1931

4 Claims. (C.I. 296—44)

In motor vehicle bodyworks, the doors are secured to the fixed pillars or uprights by means of the door lock, which is located at the middle part of the vertical edge of the door.

This mode of fixation through a single point is not sufficient for preventing the upper part and the lower part of the door from rattling, due to its being elastically deformed in a transversal direction, i. e., to its being moved laterally with respect to its frame under the effect of pot-holes and bumps in the road surface, which produces a disagreeable noise. Furthermore, due to that imperfect fixation of the door, the hinges and the mechanism for maintaining the lock-bolt get prematurely worn.

The main object of my invention is to obviate these drawbacks.

According to the present invention, the door is provided with two locks, which are disposed, one at the upper part, and the other at the lower part of the door, and said locks are adapted to engage two stumps or lugs, preferably of a conical shape, which are elastically mounted on the longitudinal element of the roof and on the body bottom side or the floor of the car respectively. These locks are preferably disposed as close as it is possible to the free vertical edge of the doors, that is to the edge opposed to the one which carries the hinges of the door.

Owing to that arrangement, the intermediate upright or pillar, in the case of a bodywork having two doors opening in opposite directions, may be dispensed with, the adjacent vertical edges of the doors being in contact with each other. The roof is thus no longer subjected to the deformations of the body bottom, and the whole of the doors, which is elastically mounted on the one hand on the roof, and on the other hand on the body bottom sides, forms an elastic bracing between the scuttle upright or front pillar, and the rounded back upright or rear pillar.

According to an embodiment of my invention, the locking stumps or lugs which serve to maintain the door are fitted with silentblocs, in the manner disclosed in my prior French Patent No. 606,499, filed Dec. 12, 1929, and my U. S. Patent application Ser. No. 470,217, filed July 23, 1930.

Furthermore, it will be found advantageous to fit the upper silentbloc on the longitudinal side member of the roof in such manner that its axis is vertical, while the lower silentbloc, which must support a part of the weight of the door, is so mounted on the body bottom side that its axis is horizontally and transversally disposed.

However, in some cases, and in particular when

the rigid roof forms a block that cannot be deformed, the reverse arrangement could be used, the door being, so to speak, suspended to the roof. Of course, any other arrangement might as well be utilized.

Lastly, the two locks of each door are controlled by means of a handle or any other suitable organ disposed half way up the door side, and connected to the lock mechanisms through two rods, cables, chains, etc., in a manner similar to the locking arrangement of a French window.

Preferred embodiments of my invention will be hereinafter described with reference to the accompanying drawings, given merely by way of example, and in which:

Fig. 1 is a cross section on the line 1—1 of Fig. 2, showing the locking and supporting arrangement according to my invention;

Fig. 2 is a plane view corresponding to Fig. 1 showing the upper locking devices provided with silentblocs;

Fig. 3 is a sectional view on the line 3—3 of Fig. 1 showing the lower locking devices provided with silentblocs;

Fig. 4 is a diagrammatical elevational view of a motor car provided with a bodywork according to my invention;

Figs. 5 and 6 are detail views corresponding to Fig. 1 showing the upper and lower locking devices of the door.

In the embodiment shown in Fig. 1, which shows in cross section a bodywork according to my invention, door *b* is locked, at its upper part, to the side member of roof *c*, and, at its lower part, to the body bottom side *d*. For that purpose, the door is provided with an upper lock *e*¹ and with a lower lock *e*², which engage locking stumps or lugs *g*¹, *g*² respectively. Said lugs are secured in an elastic manner to member *c* and to bottom side *d* respectively. Locks *e*¹ *g*¹ and *e*² *g*² may be made as the lock which has been described in by U. S. patent application Ser. No. 470,217, filed July 23, 1930. In that case they comprise a conical lug *g*¹ *g*² which is adapted to be engaged and locked by movable bolts *m*¹ *m*² (Figs. 5 and 6) which is a part of the lock mechanism. Said lug is made integral with the pin of a silentbloc whose external sleeve is provided with suitable fixation plates or straps.

Figs. 5 and 6 show at an enlarged scale how the pieces are assembled. It should be noted that the upper silentbloc *h*¹ is mounted with its axis in a vertical direction, while the axis of the lower silentbloc is horizontally and transversally disposed. That arrangement is believed to be

the most suitable for avoiding vibrations, and preventing the doors from rattling and thus doing away with the disagreeable noises which result from a defective fixation of the door.

5 It will be seen in Figs. 5 and 6 that conical lug g^1 , has its axis at right angles to the axis of silentbloc h^1 , while the lower conical lug g^2 is disposed along the same line as the axis of silentbloc h^2 . That conical lug g^2 might be integral with the axis or mounted in line with it in any suitable manner.

10 In the case of a motor car having an inclosed body comprising two doors b^0 , b , as shown in Figs. 2 and 3, it may be advantageous to so dispose the doors that they open in opposite directions. In this case, the bracing between the scuttle upright or front pillar i and the rounded back upright or rear pillar j is directly ensured by the doors and the intermediate upright is dispensed with.

15 Movable bolts m^1 , m^2 (or any other movable organs playing the same part) of the upper and lower locks e^1 , e^2 of a door respectively can be controlled by means of a knob or central operating organ k which is connected through rods l , or cables, chains, etc., to the control rods n^1 , n^2 of bolts m^1 , m^2 which, by engaging suitable recesses provided in conical lugs g^1 , g^2 , lock the latter in the desired position. The transmission between handle or knob k and the locks is similar to that generally used for the closing of French windows.

20 While I have disclosed what I consider to be a preferred embodiment of my invention, it should be well understood that I do not wish to be limited thereto as there might be changes made in the arrangement, disposition and form of the parts without departing from the principle of my invention as comprehended within 25 the scope of the appended claims.

30 What I claim is:

35 1. In a motor car comprising a chassis, a body-work comprising in combination, a body bottom rigidly secured to said chassis, a rigid roof, longitudinal side members in said roof, an upright connecting said roof to said body bottom, a door hinged to said upright, a conical lug, having a horizontal axis at right angles to said longitudinal side member, a vertical silentbloc for fixing 40 said lug to the longitudinal side member of the roof, a conical lug parallel to the first mentioned one, a horizontal silentbloc for fixing the last mentioned lug to the body bottom, locking means on the upper edge of said door for engaging the 45 first mentioned lug, and locking means on the

lower edge of said door for engaging the second mentioned lug, and means for simultaneously controlling said locking means.

5 2. In a motor car including a chassis, a body-work comprising in combination, a body bottom supported by said chassis, a rigid roof, an upright connecting said roof to said body bottom, a door hinged to said upright, cooperating locking means provided on said roof and the upper edge of said door respectively, so as to engage each other in a horizontal direction, a vertical silentbloc interposed between one of said locking means and the part of the body by which it is carried, cooperating locking means carried by 10 said body bottom and the lower edge of said door respectively so as to engage each other in a horizontal direction, and a horizontal silentbloc interposed between one of the last mentioned locking means and the part of the body by which it is carried.

15 3. In a motor car including a chassis, a body-work which comprises, in combination, a body bottom supported by said chassis, a rigid roof, an upright connecting said roof to said body bottom, a door hinged to said upright, cooperating locking means provided on said roof and the upper edge of said door respectively and adapted to act in all directions, a silentbloc interposed between one of said locking means and the part of the body by which it is carried, cooperating locking means carried by said body bottom and the lower edge of said door respectively and adapted to act in all directions, and a silentbloc interposed between one of the last-mentioned locking means and the part of the body by which it is carried, one of said silentblocs being disposed vertically and the other one horizontally.

20 4. In a motor car including a chassis, a body-work which comprises, in combination, a body bottom supported by said chassis, a rigid roof, an upright connecting said roof to said body bottom, a door hinged to said upright, cooperating locking means provided on said roof and the upper edge of said door respectively and adapted to act in all directions, a vertical silentbloc interposed between one of said locking means and the part of the body by which it is carried, cooperating locking means carried by said body bottom and the lower edge of said door respectively and adapted to act in all directions, and a horizontal and transverse silentbloc interposed between one of the last-mentioned locking means and the part of the body by which it is carried.

25 MARIUS JOSEPH DASTE. 55
